UNITED STATES PATENT OFFICE.

WILLIAM M. REELY, OF MISSOULA, MONTANA.

OUTSIDE-SASH-SECURING DEVICE.

SPECIFICATION forming part of Letters Patent No. 726,192, dated April 21, 1903.

Application filed June 13, 1902. Serial No. 111,546. (No model.)

To all whom it may concern:

Be it known that I, WILLIAM M. REELY, a citizen of the United States, residing at Missoula, in the county of Missoula and State of 5 Montana, have made certain new and useful Improvements in Outside-Sash-Securing Devices, of which the following is a specification.

This invention is an improvement in fasteners for securing storm-sashes, screens, &c., 10 over window-openings; and the invention consists in certain novel constructions and combinations of parts, as will be hereinafter described and claimed.

In the drawings, Figure 1 is a cross-sectional view showing a section of the sash secured in place. Fig. 2 is a similar section showing a fastening-bracket adjusted out of engagement with the blind-stop. Fig. 3 is a detail perspective view of the fastening-bracket; and Fig. 4 shows a somewhat different construction of fastening devices from that shown in Fig. 2.

The object of the invention is to provide a cheap, simple, and efficient sash - fastener 25 which will permit the sash to be readily put in place and secured from the inside, thereby dispensing with the necessity of ladders on the outside of the building and also avoiding the marring of the window-frame with screws, 30 hooks, or the like, as is now commonly practiced.

The sash-frame A may be that of a screen or of a storm-sash or other form of sash which it may be desired to apply to the outer side 35 of a window-opening and may be of any ordinary or desired construction. The fastening-bracket B, of which I may use any desired number on each side of the sash, may be constructed, as shown in detail in Fig. 3, with a 40 face or main plate B', provided with a slot B², elongated in the direction of length of the plate B', a returned spring-wing B³ at one end of the plate B', an abutting wing B⁴, extending from the opposite end of the plate B', at a 45 right angle thereto, and the tongue B⁵ of reduced thickness, which extends from the free end of the wing B⁴, at a right angle thereto, as shown in Figs. 1, 2, and 3. When applied as shown in Fig. 1, the main plate B' is secured by the screw C, a washer D being in-

roduced between the head of the screw and the plate B'. The wing B⁴ abuts the blind-stop E, and the tongue B⁵ of reduced thickness fits between the blind-stop E and the inside sash F and being thinned down or reduced 55 in thickness does not interfere with the free movement of the inside sash F, as will be readily understood. Manifestly the screw C may be tightened up to secure the sash A, and by means of the returned tongue B³, which 60 will operate as a spring, will serve to take up all slack and prevent the jarring or rattling of the storm-sash.

In Fig. 1 the fastening-bracket is shown in the position in which it secures the storm-sash 65 in place, while in Fig. 2 it is shown released and adjusted inwardly with respect to the outer edge of the storm-sash, so it can be readily applied to or removed from the window-casing. The fastening-bracket may be 70 made of any suitable sheet metal and can be applied for use in the manner shown in Figs. 1 and 2.

While it may be preferred to employ the returned spring-wing B³ as shown in Figs. 1, 75 2, and 3, I may in some instances employ the construction shown in Fig. 4, wherein the spring-wing B³ is omitted and the face-plate or main slotted plate of the bracket rests flat against the inner side of the sash-frame or as 80 near to said face as it can be drawn by the action of the screw.

The construction is simple, inexpensive, easily applied, readily adjusted, and will not mar or otherwise injure the window-frame. 85

Having thus described my invention, what I claim as new, and desire to secure by Letters Patent, is—

1. A sash-fastening bracket having a main plate provided with a longitudinal slot for a 90 screw, and with a wing to abut the edge of the blind-stop and a tongue to overlap the inner face of said stop, substantially as set forth.
2. In a sash-frame fastener, a fastening-bracket composed of sheet metal and having 95 a main plate provided with a longitudinal slot, the returned spring-wing at one end of the main plate, an abutting wing at the other end of the main plate and at a right angle thereto, and the tongue or wing at the free 100

end of the abutting wing and at a right angle thereto, substantially as set forth.

3. A fastening-bracket for securing outside sashes and composed of a main plate having an opening for the fastening-screw and provided at one end with a returned spring portion and at its other end with means for en-

gagement with the blind-stop and between the same and the inside sash substantially as and for the purpose set forth.

WILLIAM M. REELY.
